(57) **CLAIM**

The ornamental design for a bag for packaging, as shown and described.

DESCRIPTION

1. Bag for packaging

1.1 : Perspective

1.2 : Front

1.3 : Left

1.4 : Right

1.5 : Top

1.6 : Bottom

1.7 : Unfolded

1.8 : Unfolded

1.9 : Unfolded

The back view is omitted because it is identical with the front view; reproductions 1.1 to 1.6 show the design in its folded form from different angles, whereas reproductions 1.7 to 1.9 show the design in its unfolded form so as to serve as a picnic surface; the dashed lines in the folded views of reproductions 1.1 to 1.6 represent perforations that allow an upper portion of the product to be removed, which upper portion is not shown as part of the product in the unfolded views of reproductions 1.7 to 1.9; the dotted lines in the unfolded views of reproductions 1.7 to 1.9 indicate where the product had been folded in the folded views of reproductions 1.1 to 1.6, do no illustrate ornamentation or decoration on the surface of the product, and form no part of the claimed design.
